J. W. WALDEN.
INDICATOR.
APPLICATION FILED NOV. 6, 1917.

1,265,839.

Patented May 14, 1918.

UNITED STATES PATENT OFFICE.

JOHN W. WALDEN, OF OKLAHOMA, OKLAHOMA.

INDICATOR.

1,265,839.

Specification of Letters Patent. Patented May 14, 1918.

Application filed November 6, 1917. Serial No. 200,594.

To all whom it may concern:

Be it known that I, JOHN W. WALDEN, a citizen of the United States, residing at Oklahoma city, in the county of Oklahoma and State of Oklahoma, have invented certain new and useful Improvements in Indicators, of which the following is a specification, reference being had to the accompanying drawings.

10 This invention relates to certain improvements in indicators and has relation more particularly to a device of this general character especially designed and adapted for use in connection with railway train orders and it is an object of the invention to provide a device of this character having novel and improved means whereby an engineer, conductor, or other member of a train crew can be reminded of the different points on 20 a run of a train for which orders have been received so that the possibility of accidents, such as head on or rear end collisions, owing to forgetfulness will be substantially eliminated.

25 It is also an object of the invention to provide a novel and improved indicator of this general character consisting of a casing provided with a chart denoting the various stations on a train run or division together with adjustable and removable indices co-acting with said chart to identify certain stations or points for which train orders have been issued.

35 The invention consists in the details of construction and in the combination and arrangement of the several parts of my improved indicator wherein certain important advantages are attained and the device rendered simpler, less expensive and otherwise 40 more convenient and advantageous for use, as will be hereinafter more fully set forth.

The novel features of my invention will hereinafter be definitely claimed.

In order that my invention may be the 45 better understood I will now proceed to describe the same with reference to the accompanying drawings wherein:

50 Figure 1 is a view in elevation of an indicator constructed in accordance with an embodiment of my invention, the securing means therefor being embodied;

55 Fig. 2 is an enlarged fragmentary sectional view taken through my improved indicator showing the same in applied position; and

Fig. 3 is an enlarged fragmentary hori-

zontal sectional view taken through an end portion of my improved indicator as herein set forth.

As disclosed in the accompanying drawings 60 1 denotes a plate of predetermined dimensions and preferably rectangular in form and which has its lower horizontal marginal portion provided with a forwardly directed flange 2 with which suitable means 2^a is adapted to co-act for maintaining the plate 1 in applied position. In practice it is preferred that the device be suitably positioned in close proximity to the steam and air gage on a locomotive or in a 65 coach or caboose near the conductor's desk so that the engineer, conductor or other member of the train crew will have the device substantially constantly displayed before their gaze.

70 The end marginal portions of the plate 1 is provided with the forwardly directed flanges 3 and the outer longitudinal margin of each of said end flanges 3 is provided with an inturned supplemental flange 4 and 75 which flange 4 is herein disclosed as of double thickness. The upper marginal portion of the plate 1 has hingedly connected thereto as at 5 the top plate T which is adapted to overlie the upper end portions 80 of the end flanges 3 and to close the upper portion of the case or container as afforded by the plate 1 and the bottom flange 2 and the end flanges 3. The flanges 4 terminate a predetermined distance above the bottom 85 flange 2.

90 Disposed longitudinally of the case or container is the partition plate 6 parallel to the plate 1 and provided at its ends with the forwardly directed flanges 7 secured to 95 the end flanges 3. The outer marginal portions of the flanges 7 are provided with the inwardly directed flanges 8 also of double thickness. Each of the flanges 8 is in predetermined spaced relation relative to the 100 adjacent flange 4 to afford a guideway to snugly receive the transparent plate 9 adapted to overlie the forward faces of the casing or container. The lower ends of the flanges 4 and 8 are substantially flush 105 and the space therebetween is closed by the plate 10 or the like whereby the downward movement of the transparent plate 9 is limited and which serves to maintain the lower marginal portions of said plate spaced a 110 predetermined distance above the bottom flange 2. The lower marginal portion of the

partition plate 6 is provided with an inwardly directed flange 11 extending through the plate 1 whereby a compartment is afforded to receive the charts C not in use.

- 5 Each of the plates 10 also extends to the lower marginal portion of the partition plate 6 to afford a rest or support for the chart C in applied position. Each of the charts C is provided along its lower marginal portion with a longitudinal series of fields 12 in which are adapted to be inserted in sequence the stations along a train's run or within a division and said chart in vertical alignment with each of the fields 12 is 10 provided with the blocks 14 adapted to contain the train time.

Supported by the side flanges 3 at a point below the lower end of the flanges 4 and 8 is a horizontally disposed rod 15 angular in cross section and preferably having its forward face 16 arranged on a bevel. Co-acting with the rod 15 are the indicating members or pointers 17. As herein disclosed each of the members or pointers 17 20 comprises an elongated arm adapted to have an end portion extend rearwardly of the plate 9 and overlie a chart C while the opposite or lower end portion of said arm is returned upon itself as at 18 and which returned portion is continued in the forwardly directed extension 19 terminating in the downwardly and inwardly directed arm 20. The free or lower end portion of the arm 20 is provided with the outwardly and forwardly directed finger piece 21 whereby the indicating member or pointer 17 may be conveniently adjusted. The returned portion 18 and the arm 20 afford resilient jaws adapted to frictionally engage the rear faces 30 of the rod 15 and the forward bevel faces 16 thereof so that the member or pointer 17 may be readily positioned at a predetermined point longitudinally of the rod 15. It will also be self evident that the spring 40 jaws as afforded by the returned portion 18 and the arm 20 permit the member or arm 17 to be readily applied to or removed from the rod 15 in accordance with the requirements of practice.

50 In use, when an engineer or other member of a train crew receives train orders he positions a member or arm 17 upon the rod 15 to overlie a field 12 in which is arranged the station or locality identified by the train order. In the use of my improved indicator the engineer or other person may position the pointers or arms 17 at the proper place relative to the chart C to denote the position of a train in advance or at the rear so that he may at all times be able to determine the condition of the track.

By placing my indicator in the cab adjacent the steam and air gage it will be at once self evident that as the engineer glances at 60 the gage his attention will be directed by

the members or pointers 17 as to the various train orders which he may have received so that the possibility of collision as a result of forgetfulness on his part is substantially eliminated. This is also true of a conductor or other member of a train crew as it is intended that the indicator be placed in such a position in a coach or caboose as to fall within the gaze of a member of the crew at frequent intervals.

70 The partition plate 6 may be held in applied position in any desired manner although it is preferred that the flanges 7 thereof be seated or otherwise fixed to the end flanges 3. It is also to be understood that other connected portions of my device may be secured one to the other in a manner which best meets the requirements of practice. It is also to be understood that the rod 15 is so positioned relative to the lower end of the plates 6 and 9 and the arms or indices 17 of such a length as to 75 permit said arms or pointers to be applied into operative position relative to the chart C without necessarily removing the plate 9.

80 From the foregoing description, it is thought to be obvious that an indicator constructed in accordance with my invention is particularly well adapted for use by reason of the convenience and facility with 85 which it may be assembled and operated and it will also be obvious that my invention is susceptible of some change and modification without materially departing from the principles and spirit thereof and for this reason 90 I do not wish to be understood as limiting myself to the precise arrangement and formation of the several parts herein shown in carrying out my invention in practice except as hereinafter claimed.

95 I claim:

1. An indicator comprising a container having one face open, a transparent plate substantially closing the open face of the container but terminating a distance above the lower wall of the container, a partition plate arranged within the container to afford a rear compartment, a chart, means for supporting the chart in front of the partition plate, a rod supported by the sides of the 100 container below the transparent plate, and an index detachably and slidably engaged with the rod and of a length to extend rearwardly of the transparent plate and to overlie the chart positioned in advance of the 105 partition.

110 2. An indicator comprising a container having one face open, a transparent plate substantially closing the open face of the container but terminating a distance above the lower wall of the container, a partition plate arranged within the container to afford a rear compartment, a chart, means for supporting the chart in front of the partition plate, a rod supported by the sides of the 115 container below the transparent plate, and an index detachably and slidably engaged with the rod and of a length to extend rearwardly of the transparent plate and to overlie the chart positioned in advance of the 120 partition.

125

5 container below the transparent plate, an index detachably and slidably engaged with the rod and of a length to extend rearwardly of the transparent plate and to overlie the chart positioned in advance of the partition, said pointer being provided with spring jaws directed to frictionally engage the rod.

10 3. An indicator comprising a container having one face open, a transparent plate substantially closing the open face of the container but terminating a distance above the lower wall of the container, a partition plate arranged within the container to afford 15 a rear compartment, a chart, means for supporting the chart in front of the partition plate, a rod supported by the sides of the container below the transparent plate, an index detachably and slidably engaged with the rod and of a length to extend rearwardly of the transparent plate and to overlie the chart positioned in advance of the partition, and a hinged closure member for 20 the top of the container.

25 4. An indicator comprising a plate, a forwardly directed flange carried by a longitudinal margin of the plate, forwardly directed flanges carried by the end margin of the plate, inwardly directed flanges carried by said last named flanges, a partition plate interposed between the end flanges and spaced relatively to the first named plate, forwardly directed flanges carried by the ends of the partition plate and secured to the end flanges of the partition plate and

spaced relatively to the inwardly directed flanges of the end flanges, a transparent plate slidably engaged between the inwardly directed flanges of the end flanges and the partition plate, a chart supported in advance of the partition plate, and a pointer movable longitudinally of the partition plate and overlying the chart.

5. An indicator comprising a container having one face open, a transparent plate substantially closing the open face of the container but terminating a distance above the lower wall of the container, a chart, means for supporting the chart rearwardly of the transparent plate, a rod supported by the sides of the container below the transparent plate, said rod being angular in cross section and having its forward face arranged on a bevel, an index having an end portion provided with relatively movable jaws detachably and slidably engageable with the rod, said index being of a length to overlie the chart, the jaws of the index member frictionally engaging the rear and forward faces of the rod, the free end portion of the jaw engaging the forward face of the rod being provided with a forwardly directed finger.

In testimony whereof I hereunto affix my signature in the presence of two witnesses.

JOHN W. WALDEN.
